United States Patent Office

Des. 209,437
Patented Nov. 28, 1967

209,437

COMBINED ILLUMINABLE HAND MIRROR AND STAND THEREFOR

Matthew J. Rothman, 21 Schenk Ave.,
Great Neck, N.Y. 11021

Filed Dec. 1, 1965, Ser. No. 13

Term of patent 3½ years

(Cl. D86—10)

FIG. 1

FIG. 2

FIG. 3

FIG. 4

FIG. 1 is an exploded, front elevational view of the combined illuminable hand mirror and stand therefor, showing my new design;

FIG. 2 is a side elevational view with the mirror fitted into the seat of the stand; the side opposite thereto being a mirror image thereof;

FIG. 3 is a rear elevational view of the same; and

FIG. 4 is a top plan view of the mirror stand.

I claim:

The ornamental design for a combined illuminable hand mirror and stand therefor, substantially as shown.
